Joan E. Kinsley

UNITED STATES PATENT OFFICE.

S HAINES PLUM, 2D, OF MADISON, AND PERCY L. SIBOLE, OF NEWARK, NEW JERSEY,
ASSIGNORS TO KEYMAX FEEDER COMPANY, A CORPORATION OF NEW JERSEY.

GRIPPING MECHANISM FOR PRINTING PRESSES.

Application filed August 30, 1924. Serial No. 735,059.

To all whom it may concern:

Be it known that we, S HAINES PLUM, 2d, residing at Madison, Monroe County, New Jersey, and PERCY L. SIBOLE, residing at Newark, Essex County, New Jersey, both citizens of the United States, have invented certain new and useful Improvements in Gripping Mechanisms for Printing Presses, of which the following is a specification.

10 This invention relates to improvements in gripping mechanisms for printing presses of the character disclosed in the U. S. Patent No. 1394103, dated October 18, 1921,

15 The object of the invention is to improve generally said gripping mechanisms with a view of obtaining greater efficiency and safety of operation.

20 The invention will be more fully understood from the following specification read in connection with the accompanying drawing in which—

25 Fig. 1 is a view of a portion of a printing press equipped with the gripping mechanism aforesaid, and embodying the invention with parts in section and parts broken away.

30 Fig. 2 is a plan view of the gripping mechanism with parts in section and parts removed.

35 Only so much of the gripping mechanism is shown as is necessary for a complete understanding of this invention. For further detailed disclosure reference is hereby made to the patent aforesaid. For the purpose of ready reference thereto the parts in the drawing hereto attached which correspond to like parts in the said patent are numbered with like numbers.

40 As set forth in the said patent, the gripping mechanism illustrated therein is part of an automatic feeding mechanism attached to a Chandler & Price job press. In the present case, the press is identified by the frame III in which the platen 6 is pivoted at 5. On the frame of the press there are secured two brackets only one of which is shown and numbered 18. To the latter is pivoted at 21, a paper feed table 24 which supports the paper feeding and gripping mechanisms generally. The gripping mechanism herein referred to is a mechanism for delivering the sheet by removing it from the

platens. The table 24 is adapted to be raised and lowered on the pivot 21 by means of levers 28 and 29. Thereafter the entire table 55 with the mechanisms thereon may be swung to one side to permit the press to be hand fed or for other reasons.

45 The gripping mechanism comprises in general a gripper carriage 112 which slides 60 on two rods 110 and 111 secured to the table 24. The gripper carriage is guided by a suitable guiding bearing 115. On the gripper carriage is mounted a delivery gripper 130 suitably operated by means not 65 shown to seize the printed sheet and remove it from the platen.

55 The gripper carriage and gripper is reciprocated by a link 124 pivoted to a bearing 119. The bearing 119 slides on a rod 70 120 in the bracket 18. The link 124 is operated from any suitable part of the press. Suitable latching means 117 on the gripper carriage is adapted to engage the bearing 119 and automatically connect the gripper carriage to the link 124, and to be automatically disconnected therefrom. 75

60 As stated in the said patent, when the table 24 is to be raised and swung to one side, it is necessary to move the gripper 130 80 in under the table to prevent breakage and permit free access to the press parts adjacent thereto. In other words, when the table 24 is raised, the operator must first withdraw the gripper from the platen for 85 the sake of safety of operation. Heretofore this has been accomplished by connecting the gripper carriage to the lever 28 by a cable or band so that when the said lever was moved to raise the table 24, the gripper 90 would be automatically withdrawn. But serious objections have been found to exist against this manner of withdrawing the gripper and that the said connection might break or otherwise become inoperative. 95

65 It is therefore, the object of this invention to provide improved means for withdrawing the gripper preparatory to the raising of the paper feed table. In connection here- 100 with means are provided for positively unlocking the paper feed table from the bracket on which it rests and to which it is normally locked. And the said means are further arranged to automatically lock the

table to the bracket when the table is lowered. To this end there is mounted on the feed table 24 a sliding bolt 10 which is supported in a fixed bearing 11 secured to the table 24. The other end of the bolt passes through a hole 12 in the table casing, see Fig. 1. The end of the bolt is adapted to enter a recess 13 in the bracket 18. Said recess has an overhanging lip 19 provided with a bevel 20.

The bolt 10 is urged into said recess by a spring 211 acting against a collar 22 secured to the bolt. On the latter is also slideably mounted a catch 23 which projects into the path of the aforesaid gripper carriage bearing 115. The catch has a handle 25.

During the normal operation of the gripper, the carriage 112 is reciprocated by the link 124 in synchronism with the movements of the press and the gripper seizes and delivers the printed sheet as usual. During this operation it will be noted that the catch 23 will have been moved to the extreme right in the drawing by the movement to the right of the gripper carriage. Also it will be noted that during this normal operation the feed table 24 is locked to the bracket 18 by the sliding bolt 10.

When for some reason it is desired to raise the feed table 24 and swing it to one side, it is obvious that the gripper carriage and gripper must first be moved to the extreme left position in the drawing to withdraw the gripper under the table for the reasons aforesaid. To accomplish this operation the operator first manipulates levers 28 and 29 to slightly raise the table 24 and thereby automatically disengage the bearing 119 from the gripper carriage 112. During this movement the rod 10 moves in the curved recess 13. Almost at the same time the operator also takes hold of handle 25 and moves it to the left in the drawing during which movement the catch 23 encounters the gripper carriage and withdraws it in under the table 24. When the catch 23 strikes the collar 22 the gripper will have been completely withdrawn. The movement of catch 23 is continued to compress the spring 211 to withdraw rod 10 from the recess 13 when by continued manipulation of the levers 28 and 29 the table 24 will be completely raised and swung to one side. As soon as the table has been raised completely the operator lets go of the handle 24 and the spring 211 then moves the bolt 10 into normal position where it protrudes from the table casing.

When the table is again to be lowered, the operator manipulates the levers 28 and 29 in the reversed direction and lowers the table. When the protruding bolt 10 comes in contact with the upstanding part of bracket 18, it is forced back against the spring 211 by striking the bevel 20 and as

the lowering motion is continued, the bolt 10 snaps in under the lip 19 into the recess 13 to automatically lock the table 24 in position.

When now the press starts to operate, the operating rod 124 will move the bearing 119 in under and in contact with the latching mechanism 117 which will automatically connect the bearing with the gripper carriage and gripper. As the gripper carriage begins its movements it will engage the catch 23 and again move it to the right ready for the next raising operation. It will therefore be seen that this invention provides automatic locking means for the paper feed table and means for insuring the withdrawal of the gripper in under the table before the latter can be completely unlocked. Also that as a matter of safety, the operator must use his two hands to accomplish the result, thus focussing his attention on the work.

The automatic disengagement and reengagement of the gripper carriage with the bearing 119 is fully disclosed in the patent referred to above.

The means herein disclosed are simple in construction and certain in operation. The advantages with respect to safety and surety of operation are very important preventing breaking of parts and loss of time.

We claim:—

1. In a printing press, a platen, a bracket secured to the press and having a recess, a paper feed table pivoted on said bracket, a gripping mechanism movably mounted on said table, a bolt adapted to engage said recess to lock the table and the gripping mechanism to the bracket in normal operative relation to the platen, means for moving said gripping mechanism away from the platen and for releasing the said bolt from the said recess and other means for raising said gripping mechanism and feed table away from the said platen.

2. In a printing press, a platen, a bracket on said press having a recess, a paper feed table pivoted on said bracket, a gripping mechanism movably mounted on said table, a bolt, a spring for forcing said bolt into the said recess to lock the table and gripping mechanism in normal operative relation to the platen, a catch slidably supported on said bolt, a handle for operating the said catch to move the gripping mechanism in under said feed table and release the said bolt from the said recess, other means for raising the gripping mechanism and feed table away from the platen, the said bolt being adapted to enter said recess to automatically lock the table and gripping mechanism to the bracket after the same has been moved back into normal operative relation to the platen.

3. The combination with a press, of a gripping mechanism of the character de-

scribed comprising supporting means, means for operating the gripping mechanism thereon, a spring actuated bolt for automatically locking the said supporting means and gripping mechanism to the press while said mechanism is being operated and a device for moving the gripping mechanism into a predetermined inoperative position on the said supporting means and for moving said bolt against the force of its said spring from locking engagement with the said press.

S HAINES PLUM, 2d.
PERCY L. SIBOLE.
